UNITED STATES PATENT OFFICE.

HORACE L. COLE, OF WILKINSBURG, PENNSYLVANIA, ASSIGNOR TO WESTINGHOUSE ELECTRIC & MANUFACTURING COMPANY, A CORPORATION OF PENNSYLVANIA.

THREE-PHASE SHELL-TYPE TRANSFORMER.

Application filed August 6, 1923. Serial No. 655,838.

My invention relates to electrical transformers of the shell type and more particularly to the core structures thereof.

One object of my invention is to provide a core structure for an electrical transformer in which the quantity of metal in the core structure is materially reduced.

Another object of my invention is to provide a transformer having a core structure such that only a very small amount of metal is needed in excess of that which is actually covered by the transformer coils.

A further object of my invention is to provide a core structure for polyphase transformers in which a small number of similar parts constitutes the supporting structure for the transformer as well as the magnetic circuits thereof.

A still further object of my invention is to provide a transformer in which a small number of similar parts is provided, whereby the structure is provided with adequate ventilating facilities.

In the accompanying drawings,

Figure 1 is a view, partially in elevation and partially in section, of a polyphase transformer embodying my invention.

Fig. 2 is a view, partially in plan and partially in section, of a polyphase transformer embodying my invention.

Fig. 3 is a diagrammatic arrangement of core members and coils embodying my invention.

In the several figures of the drawing, similar reference numerals indicate like parts.

In the preferred form of my invention, I provide a polyphase transformer with a core member comprising a plurality of pairs of sections 1 and 2. The sections 1 are placed in alinement and in juxtaposition in the transformer casing, while the sections 2 are placed at the opposite ends of the aligned sections 1.

As shown in Fig. 3, the sections 1 are of substantially hollow rectangular shape and are divided by partitions 3 into longitudinally extending slots 4. The members 2 are of substantially rectangular shape, one of their dimensions being the same as one of the partitions 3, while the other dimension is substantially one-half that of the corresponding dimension of the section 3, thereby defining single slots 5. The sections 1 and 2 may be formed of any suitable mag-

netic material and they may be built up from suitable punchings or they may be formed solid, as desired.

Suitable windings 6 and 7 are mounted upon the sections 1 and 2 in such manner that the adjacent edges of two of the sections comprise the core member for the primary and secondary windings for each phase of the polyphase circuit. By so placing the sections 1 and 2 relative to one another that small spaces 8 are left between them, adequate ventilation of each coil is assured.

By reason of the shape of sections 1 and 2, I am enabled to achieve a substantial reduction in the amount of metal heretofore necessary in the construction of such core members. It is to be observed that each core member for the individual windings 6 and 7 comprises a side wall of at least two of the sections. By reason of placing two of these sections in mechanical juxtaposition, in order to furnish the necessary amount of metal for the core for each separate phase, I am enabled to materially reduce the amount of metal in either section. Furthermore, by means of my improved arrangement, the central partitions 3, together with the extreme walls of the sections 2, comprise the portions of my transformer core which are not surrounded by coils.

It will be seen that I have provided an improved core for polyphase transformers which comprises a small number of similar parts and in which there is a material saving in the amount of material needed without sacrificing any of the efficiency of the transformer, either by the crowding of the magnetic flux or by eliminating the ventilating facilities.

It is to be understood that various changes and modifications may be made in the assembly and arrangement of the several features of my invention without departing from the spirit and scope thereof, as set forth in the appended claims.

I claim as my invention:

1. In a transformer, a core member comprising a series of multi-slotted sections, and a pair of single slotted end sections.

2. In a transformer, a core member comprising a series of multi-slotted sections, and a pair of single slotted end sections, said single slotted sections being placed in alinement with said multi-slotted sections.

3. In a transformer, a core member comprising a plurality of similar multi-slotted sections in end to end relation, and a pair of single slotted end sections disposed exteriorly of the first named sections, the slots in the several sections being in parallel relation. 20
4. In a transformer, a plurality of coils, and a core member comprising a plurality of similar multi-slotted sections in juxtaposition, and a pair of single slotted sections disposed exteriorly of the first named elements, said coils being disposed in the adjacent slots of adjoining core sections. 25
5. In a core structure, a plurality of end to end sections of substantially rectangular shape, each of said sections being divided into a pair of longitudinally extending slots, and a pair of end sections having one of the dimensions of the first mentioned sections and substantially one-half of another dimension of the first mentioned sections, each of said last named sections being provided with a single slot. 30
6. In a core structure, a plurality of sections of substantially rectangular shape and extending in the same plane, each of said sections being divided into a pair of longitudinally extending slots, and a pair of end sections having one of the dimensions of the first mentioned sections and substantially one-half of another dimension of the first mentioned sections, each of said last named sections being provided with a single slot, said sections being placed with their slots in parallel relation. 35
7. In a core structure, a plurality of end to end sections of substantially rectangular shape, each of said sections being divided into a pair of longitudinally extending slots, and a pair of end sections having one of the dimensions of the first mentioned sections and substantially one-half of another dimension of the first mentioned sections, each of said last named sections being provided with a single slot, said sections being disposed with their slots in parallel relation, and with ventilating spaces therebetween. 40
- In testimony whereof, I have hereunto 50
subscribed my name this 2nd day of August
1923.

HORACE L. COLE.
